UNITED STATES PATENT OFFICE.

DAVID P. CERA, OF IRON BELT, WISCONSIN.

HAIR-SINGEING DEVICE.

1,181,840.

Specification of Letters Patent.

Patented May 2, 1916.

Application filed January 12, 1916. Serial No. 71,765.

To all whom it may concern:

Be it known that I, DAVID P. CERA, a citizen of the United States, residing at Iron Belt, in the county of Iron and State of Wisconsin, have invented new and useful Improvements in Hair-Singeing Devices, of which the following is a specification.

My invention relates to a hair singeing device for the use of barbers and hair dressers, and particularly to a hair singeing comb, the object of the invention being to provide a comb of novel construction, the said comb having a guard so disposed with relation to the teeth thereof as to hold the hair engaged by the teeth in such position that only the projecting portions of the hair follicles will be singed or burned off, thereby protecting the remainder of the hair.

A still further object of the invention is to provide a singeing comb having a fine toothed comb surface whereby, after each portion of the hair is singed, such portion may be combed out to dispose the hair in normal position.

The invention consists of the features of construction, combination and arrangement of parts herein fully described and claimed, reference being had to the accompanying drawing in which:—

Figure 1 is a view in elevation of a singeing comb embodying my invention. Fig. 2 is a vertical transverse section on line 2—2 of Fig. 1. Fig. 3 is a detail view of the body of the singeing comb illustrating a feature of construction.

In carrying my invention into practice, I provide a singeing comb 1, comprising a comb proper 2 and a handle 3 extending longitudinally from one end of said comb. The lower edge of this handle is preferably formed to provide an auxiliary or fine toothed comb 4, by which after each operation of singeing, the device may be employed in reverse position to comb out the singed hair to a normal state or condition either to dress the hair or dispose of it for further singeing.

The teeth 5 of the comb proper 2 may be of any suitable degree of fineness, and this comb may be of any preferred dimensions. As shown, the back of the comb proper 2 is provided beyond each end of the series of teeth 5 with supporting portions or arms 6 to carry a guard 7. The guard 7 is in the form of a comb substantially coextensive in size to the comb 2 and having teeth 8 which

may be of the same degree of fineness as the teeth 5. At its ends the guard 7 is provided with arms or legs 9 which rest against the outer faces of the arms 6 and are secured thereto by rivets or other suitable fastenings 10. As shown, the arms 6 are bent forwardly at an oblique angle to the plane of the teeth 5, so that the guard comb 7 will lie at an outward and downward angle to the plane of the comb 2, as clearly shown in Fig. 2.

In the use of the device, it will be understood that the comb is employed in the usual manner to engage a portion of the hair. The ends of the hair which project beyond the face of the guard comb will be burned or singed, the guard comb thus serving as an accurate gage by means of which the amount of hair to be singed off may be more easily and correctly determined. It will be observed that as the teeth of the guard comb stand off or are spaced from the teeth of the singeing comb, the body of the hair will be protected or guarded against being heated or singed, only those portions of the hair projecting through the teeth of the guard comb being singed or burned away.

A material advantage resulting from the use of my invention, incidental to those set forth, is that the operator may work with greater celerity, since it is not necessary for him to accurately gage the extent of projection of the ends of the hair, while at the same time irregularities in singeing are to a very large extent avoided. By providing the auxiliary comb surface on the handle 3, it will be evident that the operator may comb or smooth out the singed hair without recourse to a second comb, and as a result the singeing operation may be carried out in a quick and convenient manner.

I claim:

1. A device of the character described comprising a singeing comb having a handle projecting longitudinally beyond one end thereof, and a guard comb arranged upon one side of the singeing comb and at an angle thereto, said combs having their backs outwardly disposed and the points of their teeth arranged in proximity, the points of the teeth of the guard comb being arranged to overlie the points of the teeth of the singeing comb.

2. A singeing device comprising a singeing comb having a handle projecting from one end thereof, said handle being provided with a comb surface, and a guard comb ar-

ranged at one side of and at an oblique angle to the singeing comb, said combs having their backs outwardly disposed and their points of the teeth of the guard comb being arranged to overlie the points of the teeth of the singeing comb.

3. A singeing device comprising a singeing comb having a handle provided with a series of teeth and having arms beyond the terminal teeth of the singeing comb, bent laterally beyond one side of the comb, and a guard comb having similar teeth and arms,

said guard comb having the points of its teeth projecting toward the teeth of the singeing comb and overlying the same and having its arms arranged to overlie the angularly bent arms of the singeing comb and connected thereto.

In testimony whereof I affix my signature in presence of two witnesses.

DAVID P. CERA.
